 John Santalone

(57) **CLAIM**

The ornamental design for a toothbrush, as shown and described.

DESCRIPTION

FIG. 1 is a front, side perspective view of a toothbrush showing my new design;
 FIG. 2 is a top, rear perspective view thereof;
 FIG. 3 is a rear, side perspective view thereof;
 FIG. 4 is a rear view thereof;
 FIG. 5 is a side view thereof; and,
 FIG. 6 is a side, front perspective view thereof.
